COMBINATION LEG AND BACK REST

Capelle H. Archer, Richmond, Va.

Application March 21, 1940, Serial No. 325,246

6 Claims. (Cl. 155—169)

This invention relates to leg rests and particularly to a leg rest which may be used in a multiplicity of positions and which may also be used as a back rest for supporting a person in a sitting posture in bed.

An object of the invention is to provide a combination leg and back rest of simple, sturdy construction which will be free of moving parts and which when used as a leg rest will automatically adjust itself to the proper position to suit the various positions of the user.

Another object is to provide a leg rest which will adapt itself to support the weight of the legs in the most comfortable position and which will take all weight off the feet of the user.

Another object of the invention is to provide a leg rest adapted to support the legs of a person sitting in a rocking chair and which will rock about a pivot or bearing member to automatically assume the correct angle to support the legs of the user comfortably in the various positions assumed when rocking.

A further object of the invention is to provide a combination leg and back rest which when used as a back rest in a bed will not slide away from the user under the weight of the body when leaning back against the rest.

Other objects and advantages of the invention will be apparent from the following detailed description of the invention with reference to the accompanying drawings wherein:

Fig. 1 is a perspective view of a combined leg and back rest embodying the invention,

Fig. 2 is a side elevation thereof illustrating two positions of use,

Fig. 3 is a rear elevation,

Fig. 4 is a fragmentary section taken on the line 4—4 of Fig. 3,

Fig. 5 is a fragmentary section taken on the line 5—5 of Fig. 4,

Fig. 6 is a fragmentary bottom plan view of the device,

Fig. 7 is an enlarged detail view of the pivot or bearing member, and

Fig. 8 is a side elevation illustrating use of the invention as a back rest on a bed.

Referring more particularly to the drawings, 10 indicates a pair of upright rear legs and 11 a pair of front legs disposed at the corners of a rectangular base for the rest, the front legs 11 being much shorter than the rear legs 10. A cross rail 12 extends between the front legs 11 and a cross rail 13 extends between the upper ends of the rear legs 10. Side rails 14 extend

between the legs 10 and 11 at the opposite sides of the base.

The cross rails 12 and 13 serve to space the legs 10 and 11 and also support the ends of a central longitudinal bridge rail 15 which supports the central portion of an upper fabric cover or support 16, of suitable stout material, which extends between side rails 17 forming a body member support slanting downwardly from the upper ends of the rear legs. The side rails 17 extend between and are secured at opposite ends to the upper ends of the front and rear legs 10 and 11 at opposite sides of the base. The side edges of the fabric cover are preferably turned over the side rails 17 and are secured thereto by suitable fastening means such as the tacks 18. At the rear edge, the fabric cover 16 is turned over the upper edge of the rear cross rail 13 and is secured thereto, as by tacks 19.

As will be seen from an inspection of Fig. 3, the upper edge of the rear cross rail 13 follows the line of a concave curve from the center toward each end thereof so that the fabric cover defines a trough on each side of the bridge rail 15, each trough being adapted to cradle a leg of the user of the leg rest. A leather or other suitable wear-resisting strip 20 protects the fabric 16 from wear due to contact by the heels of shoes of users of the rest. Strips of upholsterers' webbing 16' underlying the fabric 16 take the strain off of the same.

A foot rest 21 is mounted between the rear legs 10 approximately midway of the height thereof, being carried by brackets 22 secured to the inner face of an intermediate cross rail 22' extending between the rear legs 10. The foot rest 21 is mounted at a comfortable angle to support the feet of a person seated in a chair facing the rest and projects at its lower end a short distance beyond the line of the rear face of the legs for a purpose to be discussed hereinafter.

The lower ends of the legs 10 are secured to a bottom cross bar 24 which functions as a bearing or rocking bar when the leg rest is in use. In the example illustrated, the rocking bar 24 has a flat top and the lower ends of the legs 10 rest on the top of the bar adjacent the ends thereof. The under side of the bar 24 in the embodiment illustrated is formed to provide a plurality of flat longitudinally extending surfaces or faces 25, 26 and 27, as seen more clearly in Fig. 7, which surfaces are at a slight angle with respect to each other. Each of the surfaces 25, 26 and 27 has a number of pads or feet 28

mounted thereon, the pads in adjacent rows being disposed in staggered relation.

The pads or feet 28 are made of anti-friction material, preferably rubber, and form an anti-slipping rocking unit which will afford a firm support for the rest when tilted to the position of use as a leg rest, as illustrated in full lines in Fig. 2. The bar 24 could be made with a curved under surface but the provision of the faces 25, 26 and 27 facilitates proper alignment of the pads 28 in each row which makes it much easier to replace the same if they eventually become worn or knocked off during use. If the under surface of the bar 24 is of uniform curvature, the same may be provided with a continuous anti-slipping covering, although I prefer to use separated anti-slipping members, such as pads 28.

The construction as described results in a rigid unit which when standing alone presents a slanting upper surface 16 disposed at an acute angle to the plane of the rear or taller legs 10 and so dimensioned that when the unit is tilted back, with the bar 24 as a pivot, to a position in which the surface 16 becomes a substantially horizontal platform, the weight of the unit will be balanced on the bar 24. Thus when the unit is tilted to this position and the legs of a person, seated facing the rear or high end of the unit, are laid on the top 16, there will be no tendency for the unit to return to its standing position but it will readily tilt about the bar 24 so that the platform top 16 assumes exactly the right angle to comfortably support the legs of the user.

While the invention is not restricted to the exact dimensions of the respective parts, the best results from the standpoint of balance of the device when employed as a leg rest are secured if the legs 10 and upper surface 16 are so dimensioned and arranged at such an angle to each other that when the device is tilted on the pivot bar 24 to occupy a position in which the platform approaches the horizontal, the weight of the unit will be balanced upon said bar. Due to the balanced condition of the rest, no effort is required to retain it in balanced position when the weight of the legs are placed on the top 16 so that all of the leg muscles can be completely relaxed.

When the device is used as a bed rest, as shown in Fig. 8, it is turned on end with the legs 10 resting lengthwise on the mattress 30 in back of the user, with the top 16 facing the back of the user. In this position, the top 16 provides a supporting surface at the correct angle to the plane of the mattress to comfortably support the user in a sitting posture. With the rest so disposed, the projecting portion 23 of the foot-board 21 and the rear edge of the bar 24 press into the mattress, as indicated at 31 and 32, thus preventing the rest from sliding away from the user when he leans back on the same.

While a preferred embodiment of the invention has been shown and described by way of illustration, it will be understood that various modifications in the details of construction may be resorted to without departing from the spirit of the invention within the scope of the appended claims.

I claim:

1. In a rest of the character described, spaced upright front and rear leg members, a body member support comprising spaced side rail members rigidly connected at the ends thereof to the upper ends of said front and rear leg

members and a cover member extending between and secured to said side rails, said support extending downwardly from the upper ends of said rear legs at a sharp angle thereto, and a rocking bearing member secured to the lower ends of said rear leg members, the relative dimensions of and the angular relation between said legs and said support being such that when said rest is tilted about said bearing member to dispose said support in substantially horizontal position, substantially the entire weight of the rest will be balanced on said bearing member.

2. In a rest of the character described, a rigid frame comprising upright front leg members, upright rear leg members longer than said front leg members, inclined side rails extending between the upper ends of the front and rear leg members, a fabric support extending across and secured to said side rails, a laterally extending bearing bar extending between and secured to the lower ends of said rear leg members, and a plurality of friction pads on the under surface of said bearing bar providing a rocking surface for said rest, the relative dimensions of and the angular relation between said rear leg members and said fabric support being such that when the rest is tilted about said bearing member to dispose said fabric support in substantially horizontal position, substantially the entire weight of the rest will be balanced on said bearing bar.

3. In a rest of the character described, a rigid frame comprising upright front and rear leg members, inclined side rails extending between the front and rear leg members, a fabric support extending between and secured to the inclined side rails, and a laterally extending bearing bar secured to the lower ends of the rear leg members, the relative dimensions and angular relation of said inclined side rails and said rear legs being such that when said rest is tilted rearwardly on said bearing bar to dispose said rails in a substantially horizontal position, the weight of said rest will be balanced on said bearing bar.

4. In a leg rest of the character described, a rigid frame comprising upright front leg members, upright rear leg members in spaced relation to and longer than said front leg members, parallel inclined side rails extending between and secured to the upper ends of said front and rear leg members, a cross rail between said front leg members, a cross rail between the upper ends of said rear leg members, an inclined center rail extending between and supported by said cross rails parallel with said inclined side rails, a fabric support extending across and secured to said inclined side and center rails to provide a leg support between said center rail and each of said side rails, a laterally extending bearing bar extending between and secured to the lower ends of said rear leg members, said bearing bar providing a rocking supporting surface for said rest.

5. In a leg rest of the character described, a rigid frame comprising upright front leg members, upright rear leg members in spaced relation to and longer than said front leg members, parallel inclined side rails extending between and secured to the upper ends of said front and rear leg members, a cross rail between said front leg members, a cross rail between the upper ends of said rear leg members, an inclined center rail extending between and supported by said cross rails parallel with said inclined side rails, a fabric support extending across and secured to

said inclined side and center rails to provide a leg support between said center rail and each of said side rails, a laterally extending bearing bar extending between and secured to the lower ends of said rear leg members, said bearing bar providing a rocking supporting surface for said rest, the relative dimensions and angular relation of said inclined side and center rails and said rear legs being such that when said rest is tilted rearwardly on said bearing bar to dispose said rails and said leg supports in a substantially horizontal position, the weight of said rest will be balanced on said bearing bar.

6. In a rest of the character described, a rigid frame comprising upright front and rear leg members, inclined side rails extending between

the front and rear leg members, a fabric support extending between and secured to the inclined side rails, a laterally extending bearing bar secured to the lower ends of the rear leg members, and a foot rest comprising an inclined footboard supported between said rear leg members intermediate the upper and lower ends thereof, said footboard having one edge projecting beyond the plane of the rear of said legs, whereby said projecting edge of said footboard will press into a resilient supporting surface of a bed or the like when said rest is positioned for use as a back rest with said rear legs extending parallel to and lying on said resilient supporting surface.

CAPELLE H. ARCHER.
